WEFT-REPLENISHING LOOM FOR WEAVING

Walter Gledhill, Huddersfield, England

Application March 6, 1936, Serial No. 67,556
In Great Britain August 21, 1934

6 Claims. (Cl. 139—238)

The invention relates primarily to weft-replenishing looms of the shuttle-changing type in which, on detection of substantial exhaustion of weft in the running shuttle, the empty shuttle is automatically removed and a full one substituted, although the improved mechanism constituting the invention may be applied to looms of the type wherein a full bobbin is substituted for an empty one in a shuttle.

10 The invention has for its object to provide improved and simplified weft-replenishing mechanism, and further so to construct or arrange such mechanism that it can, with little or no difficulty, be applied to any existing ordinary loom.

15 The characteristic feature of my improved weft-replenishing mechanism is the provision, on the lay or going-part, of one or more screw members disposed below a fixed shuttle box at one end of the loom, the bottom of the box having an opening large enough to permit of the passage of a shuttle or a weft carrier through it, and the upper end or ends of the screw member or members, when said member or members is or are at rest, being so fashioned as to form as it were a false bottom to the shuttle box and provide a surface or surfaces on which a shuttle or weft carrier may rest when it enters the box during the ordinary running of the loom. Preferably two screws, suitably spaced apart, are employed.

20 Means are provided which, when weft replenishing is called for, and the shuttle containing the empty bobbin is in position above and resting upon the upper end of the screws, cause suitable rotation to be given to the screws to cause a full shuttle or weft carrier to be elevated up to the level of the race way, such elevation raising up the exhausted shuttle or weft carrier to a position in which it is engaged by a member projecting rearwardly from the breast beam or more correctly from a magazine on the breast beam, so that as the lay goes back the empty shuttle or weft carrier is raked off the top of the new or of the running shuttle to drop into a suitably placed receptacle.

25 As the lay approaches front centre during replenishment, a transfferer operates to take a full shuttle or weft carrier from the magazine on the breast beam and place it upon the front lower parts of the threads of the worms ready for the next call for weft replenishment. The magazine is of vertical type, and the transfferer is arranged to take away the lowest shuttle or weft carrier and at the same time hold up

30 the next lowest shuttle or weft carrier until the transfferer returns to normal position, when the said next lowest shuttle or weft carrier is permitted to drop down into transfer position.

35 Suitable means are provided to hold the weft ends extending from the shuttles or weft carriers in the magazine and from that resting on the screws so that they are all in correct relative position to a thread cutter mounted on the breast beam, so that when a new shuttle or weft carrier has been brought into action the weft end extending from the selvage to the end holder is in correct position to be severed by the cutter.

40 Means may be provided to carry into the path of the cutter, on the pick on which replenishment is to take place, the weft extending from the selvage to the exhausted shuttle or weft carrier, so that the old weft is cut on the first pick after replenishment along with the new weft end.

45 Means may be provided to draw away the old weft end clear of the reserve weft end, and to remove from the exhausted bobbin any weft which may remain thereon.

50 Means may also be provided whereby, just before replenishment, the loom brake is applied to reduce temporarily the speed of the loom and thus reduce possible shocks and strains.

55 The means for actuating the screws which effect the weft replenishment, and for actuating the transfferer and other mechanisms are brought into operation by an electro-magnet situated at the replenishing end of the loom and energized when weft exhaustion is detected by a feeler situated at the opposite end of the loom.

Such being briefly the nature of the invention, a fuller and more detailed description will be given with the aid of the accompanying drawing, in which:—

Fig. 1 is a front elevation of the right hand, or replenishing, end of a loom of the shuttle-changing type having an embodiment of the invention applied thereto.

Fig. 2 is a plan view of the parts shown in Fig. 1;

Fig. 3 is an end elevation looking in the direction of the arrow 3 in Fig. 1.

Fig. 4 is a detail on a somewhat enlarged scale, illustrating the operation of weft replenishment;

Fig. 5 is detail rear view looking in the direction of the arrow 5 in Fig. 3;

Fig. 6 is a detail illustrating the weft end

holder and cutter and means for holding up into the path of the cutter the ends of weft extending from the selvage of the fabric to the empty shuttle, and from the selvage to the end holder.

Fig. 7 is a side view and Figs. 8 and 9 plan views of means for holding out the box swell to enable the empty shuttle to be ejected and the full shuttle to move in;

10 Fig. 10 is a detail plan view of a portion of the shuttle box at the replenishing end of the loom showing provision for permitting the weft end from the new shuttle to take a direct path from the weft end holder to the cutter;

15 Fig. 11 illustrates how the weft end from the empty shuttle is removed from the path of the new weft and any remaining weft stripped from the bobbin in the empty shuttle;

20 Fig. 12 illustrates how, in a modified arrangement, the picker may be moved out of the way to allow the spent shuttle to be ejected through an open end of the shuttle box at the replenishing end of the loom.

25 Referring to the drawing, *a* represents the crankshaft of the loom, *b* the picking shaft, *c* the lay, and *d* the breast beam.

30 For the purposes of the invention, I provide at one end of the lay a weft feeler of any approved construction adapted, on exhaustion of weft in the running shuttle, to close an electric circuit and energize an electromagnet *e* at the opposite or replenishing end of the loom.

35 On the breast beam at the replenishing end of the loom I provide a shuttle magazine *f* of vertical type from which, by means to be described later, the lowest shuttle can be taken and transferred to replenishing position.

40 Movable with the lay I provide two screws *g* and *h* the upper ends of which are adapted to form shuttle supports, or a false shuttle box bottom, at the replenishing end of the loom.

45 A lever *i* pivoted at *i'* on the loom frame to swing frontwardly and rearwardly, carries at its upper end a transfer member having a part *i*² adapted to take from the magazine the lowest shuttle, and a part *i*³ adapted to ride under and support the next lowest shuttle until the transfer member returns to normal position when the said next lowest shuttle is permitted 50 to drop down into transfer position. The action of the transerrer will best be understood by reference to Fig. 4 of the drawing.

55 The shafts *g'*, *h'* of the two elevating screws are geared together by toothed gears *g*² and *h*² and the lower end of the shaft *g'* is geared by bevel gears *j* and *j'* to a shaft *k* carrying a chain wheel *k'* which is connected by chain *k*² to a chain wheel *m*² on a rotatable boss *m* mounted loosely on a stud *m'* disposed below the end of the picking shaft *b*. The boss *m* carries also a toothed pinion *m*³. On the end of the picking shaft there is fast a cam *n* having on its periphery gear teeth *n'* with which, by an inward sliding movement of the boss *m*, the pinion *m*³ can be caused to mesh so as to receive a partial rotation during a revolution of the cam.

60 The boss *m* is movable axially by means of a forked member *m*⁴ pivoted at its lower end on a bracket *m*⁵ secured to the end frame of the loom. 70 Connected pivotally to the member *m*⁴ at *m*⁶ is the lower end of a lever *m*⁷ pivoted at *m*⁸ to a bracket *m*⁹ on the loom frame. The upper end of the lever *m*⁷ has a rearward projection *m*¹⁰ carrying a pivoted catch member *o*, the position of which is controlled by a weft feeler at

the opposite end of the loom. Conveniently this feeler may be of the electric type and be arranged, on detection of substantial exhaustion of weft in the running shuttle, to close a circuit through the electro-magnet *e* the armature lever *p* of which is connected to the pivoted catch member *o*.

10 The cam *n* has on its outer face a flange or strip *n*² which when the catch member *o* is in operative position enters a groove on the inner side of the said member and acts to move it laterally outwards, thus swinging the lever *m*⁷ and rocking thereby the forked member *m*⁴ which controls the axial movement of the boss *m*.

15 The catch member *o* is shown as being counterweighted at *o'* so that normally it will be held in inoperative position, and the connection *o*² to the armature lever *p* of the magnet is such that when the magnet is energized by the action of the weft feeler the connection *o*² will be raised 20 to rock the catch into operative position.

25 When the boss *m* is moved to carry the pinion *m*³ into the path of the gear teeth *n'* it is, at the appropriate time in the revolution of the picking shaft, given a partial rotation. This rotation causes the elevating screws *g* and *h* to commence to revolve and thus to elevate the full shuttle which, as will become apparent, is at this time resting on the front portions of the screw threads, as is indicated in Fig. 4. The rotation 30 of the screws may be timed to commence as soon as the empty shuttle has reached the shuttle box at the replenishing end of the loom, and may continue until the next pick from that side of the loom is due to commence. A considerable 35 time, relatively speaking, is thus available in which to effect the change of shuttles.

40 In the embodiment now being described the empty shuttle, on arrival at the replenishing end of the loom is permitted to remain in the shuttle box. As the elevating screws operate, therefore, to raise to the level of the race way a 45 full shuttle, the empty shuttle represented at *s'* in Fig. 4, is raised up into the position indicated at *s*², that is to say above the level of the top of the shuttle box.

45 Projecting rearwardly from the magazine is a hook member *r* which when the lay comes to front centre extends over the shuttle position as shown in Fig. 4. As the empty shuttle is raised 50 out of the box, therefore, the hook member enters the top of the shuttle and as the lay goes back the empty shuttle is raked off the top of the full shuttle to fall into a suitably placed receptacle.

55 In an alternative arrangement the empty shuttle may, on arrival at the replenishing end of the loom, not be retained in the box but be ejected through the open end of the box. To this end, as shown in Fig. 12, provision may be 60 made to swing the picker *t* out of the way. A boss *t'* mounted loosely on the picker spindle *t*² has pins *t*³ which straddle the picker stem, and an arm *t*⁴ which is arranged to be drawn 65 downwardly simultaneously with the inward movement of the boss *m* when replenishment is to take place. The downward drawing of the arm swings the picker out of the way as shown, a suitable opening or gap being provided in the box back for the purpose.

70 On the shaft *g'* of the screw *g* there is provided a cam *g*³ which as the lay comes forward during replenishment engages the lever *i* and operates the transfer member to transfer a full shuttle from the magazine and place it on the 75

front part of the threads of the elevating screws ready for the next replenishing operation, the full shuttle which was previously held by the screws having by this time been elevated out of 5 the way. The cam is so shaped and rotated that after it has actuated the transferrer its nose rides past the lever *i* so that the latter is not engaged as weaving proceeds.

On the front side of the magazine there is supported loosely a wire member *f'*, see Fig. 6, beneath the lower end of which the weft ends from all the shuttles in the magazine are passed to be secured to a fixed end holder *f*². The lower end of the member *f'* is disposed at such a height that when a full shuttle is picked for the first time its weft is carried into the path of the usual temple thread cutter *f*³. The member *f'* is supported loosely so that it can be lifted up each time a shuttle is placed into the magazine, 20 and the weft end be passed beneath the lower end of the member without any danger of the hand being trapped if the magazine is being charged whilst the loom is running. The full shuttle when being placed into running position is, as has been explained, elevated up 25 through the bottom of the shuttle box. To enable its weft to pass straight from the member *f'* to the selvage there is provided in the inner end of the shuttle box bottom a slot *u* see Fig. 10. The weft end can thus pass clear of the front of the box, as will be understood.

When an empty shuttle is removed from the shuttle box in the manner above described, the weft end extending from it to the selvage of the fabric crosses over the weft end extending 35 from the weft end holder to the full shuttle which is being elevated to running position. In order to get this weft end out of the way I provide, as shown in Fig. 6, a lifter cord *v* one 40 end of which extends loosely over the breast beam *d* whilst the other is held by a spring clip *v'* on the crank connector *v*². As the crank shaft rotates therefore the cord *v* is raised as 45 shown in dotted lines and lifts the spent weft end up into the path of the temple thread cutter so that such weft end is definitely cut on the first pick after removal of the empty shuttle.

As previously mentioned, the empty shuttle, 50 when removed, drops down into a suitable receptacle. In so doing it carries the weft end *w* extending from it to the selvage into the path of a suitably rotated roller *R* Fig. 11, provided with projecting wire teeth which engage and 55 catch the weft end and, as the roller rotates, the spent weft end, which by this time has been cut at the selvage, is dragged clear of the new weft and at the same time any weft remaining on the bobbin in the spent shuttle is drawn off. The roller *R* is preferably withdrawable from 60 its driving spindle and provided with a longitudinal slot to permit of cutting and removal of the collected weft ends.

In order to hold the "jammer" lever *w'* in 65 inoperative position and to withdraw the usual shuttle box swell or shuttle binder when a new shuttle is being inserted, a rod or wire connected to the lever *m*⁷ which carries the catch *o* may be suitably cranked and journalled on the loom frame so that its end *w* will, when the catch lever swings laterally to initiate replenishment, 70 be caused to move under the "jammer" lever and hold it up, such raising of the "jammer" lever being arranged, by a suitable connection, 75 to act upon and withdraw the shuttle binder.

The magazine is provided with vertical guide strips *f*⁴ to retain the shuttles. These guide strips terminate just above the lowest shuttle, and to hold the latter there are provided at the lower ends of the magazine sides and towards 5 each end of the bottom suitable blade springs which function to retain yieldingly the shuttle until operation of the transferrer. Suitable springs will also be provided in the front of the shuttle box to receive the full shuttle from the 10 transferrer and hold it in position on the screws.

When it is arranged to remove the empty shuttle over the front top of the shuttle box as has been described, I preferably provide at the top of the back of the box a yielding strip *x* 15 see Fig. 2, the said strip being normally held down by spring action to form a top guide for the shuttle and yielding vertically to permit of raising of the empty shuttle.

The inner end portion of the member *x* is 20 arranged to cooperate with a small recess in the box back so that as a shuttle enters the box it tends to force the end portion into the recess and enables the strip to yield vertically. When the empty shuttle has been raised to a certain 25 height it rides clear of the spring strip, and the spring thereupon acts to force down the strip behind the shuttle and thus assist in the forward ejecting movement of the latter.

The forked member *m*⁴ which functions to 30 give axial movement to the boss *m* to initiate replenishment is provided with a projection, not shown, which is engaged by the cam *n* at the appropriate time and causes the said member to be swung in a direction to move the boss outwardly and thus stop the action of the replenishing 35 mechanisms.

It may be desirable, in order to avoid shocks, to slow down the loom prior to and during replenishment. To this end the usual brake connector *y* may be fashioned with inclined slots *y'*, *y*² to receive respectively the thin pin *y*³ on the sliding stop member *w*³ and the pin *y*⁴ on the usual pivoted brake block holder *y*⁵. A cam *y*⁶ movable with the boss *m* is adapted, when the boss is moved inwardly, to engage and rock a pivoted angle member *y*⁷ and thus raise the connector *y*, the effect of such raising being to cause as shown in Fig. 3, through the inclined slots, an endwise movement of the connector 40 sufficient to apply the brake, this action being quite independent of the usual application of the brake through the action of the "jammer" lever. 45

The provision of the inclined slots in the connector *y* also enables the usual separate weft stop motion brake to be dispensed with. A connection *y*⁸ is made to a rod *y*⁹ movable vertically when the weft stop motion operates, and adapted to move downwardly the front end of the connector thus giving to it an endwise movement 55 and applying the brake. The connector *y* functions, therefore in three ways, firstly as a knock-off brake member under a direct pull from the member *w*³, secondly as a weft stop brake member as just described, and thirdly as a slow 60 down brake member prior to and during replenishment.

In order to minimize any shock which may occur when commencing a replenishing operation, the chain *k*² which conveys drive to the elevating screws may pass over a bowl *k*³ on a spring-actuated jockey lever *k*⁴ so that the drive is started gradually. A connection from the jockey lever *k*⁴ is led to the usual knock-off lever so that in the event of any obstruction 70 75

causing an undue movement of the jockey lever the loom will be stopped.

In applying the invention to a loom of the type in which a full bobbin or weft carrier is substituted for an empty one in the running shuttle the magazine and transerrer will be appropriately modified to deal with bobbins or weft carriers. The yielding strip x will not be required, and the top of the box may have fixed strips both at the front and back to hold the shuttle down during replenishment.

Having thus described my invention, what I claim as new and desire to secure by Letters Patent is:—

- 15 1. In a shuttle changing loom, a fixed shuttle box at one end thereof, a vertical screw member disposed beneath the said box with its upper end forming a false bottom thereto, said screw member being adapted to support a full shuttle 20 on its thread below the upper end of the thread, and means operable upon weft exhaustion in the running shuttle for rotating said screw member in a direction to raise a full shuttle into the shuttle box.
- 25 2. The combination with mechanism according to claim 1, of a fixed full-shuttle magazine at the front of the loom and means operable upon weft exhaustion to transfer a full shuttle from said magazine on to the thread of the 30 screw member.

3. The combination, with mechanism accord-

ing to claim 1, of a fixed full-shuttle magazine at the front of the loom, means operable upon weft exhaustion to transfer a full shuttle from said magazine on to the thread of the screw member, and a rearwardly extending hook member carried by the magazine, said hook member being engageable in the top of an empty shuttle as the latter is raised out of the shuttle box during shuttle changing whereby to rake said empty shuttle off the top of a newly inserted 10 shuttle as the loom lay goes back.

4. In mechanism according to claim 1 an open outer end to the shuttle box, a picker adapted to pick out a shuttle from the said box, and means to move the said picker clear of 15 the box when shuttle changing is to be effected.

5. In mechanism according to claim 1, a shuttle binder in the fixed shuttle box, and means to render said binder inoperative while 20 shuttle changing is taking place.

6. In a mechanism according to claim 1, a pulley on the loom crank shaft, a brake operable thereagainst, means to operate said brake to stop the loom, a connector between said means and said brake, and separate brake actuating means associated with said connector and 25 operable by initiation of shuttle changing to cause the brake to be applied independently of said brake operating means.
